UNITED STATES PATENT OFFICE.

WILLIAM S. PROUDFIT, WILLIAM H. EDWARDS, AND ALEXANDER F. WINTERS, OF GRAND RAPIDS, MICHIGAN; SAID WINTERS ASSIGNOR TO SAID PROUDFIT AND SAID EDWARDS.

LOOSE-LEAF BINDER.

1,249,666.

Specification of Letters Patent.

Patented Dec. 11, 1917.

Application filed December 16, 1915. Serial No. 67,102.

To all whom it may concern:

Be it known that we, WILLIAM S. PROUDFIT, WILLIAM H. EDWARDS, and ALEXANDER F. WINTERS, all citizens of the United States, 5 residing at Grand Rapids, in the county of Kent and State of Michigan, have invented new and useful Improvements in Loose-Leaf Binders, of which the following is a specification.

10 The present invention relates to loose-leaf binders; and its object is generally, to provide such a binder which shall be simple and economical in construction; and more particularly, such a binder having simple 15 and readily-operable adjusting means.

These objects are attained by, and the invention finds preferable embodiment in, the structure hereinafter described and illustrated in the accompanying drawings, in 20 which:

Figure 1 is a plan view of the inside of a loose-leaf binder opened out flat:

Fig. 2 is a fragmentary view in perspective of the same:

25 Fig. 3 is a sectional view of certain parts on line 3—3 of Fig. 1:

Fig. 4 is a like view of certain parts on line 4—4 of Fig. 1, and

30 Fig. 5 is a like view of the roughened surface of one cover, adapting it to secure the leaf-holding member against sliding or slackening movement.

In the embodiment of the invention chosen for illustration by the drawings and 35 for detailed description herein, the covers 1 and 2 are connected by a flexible back 3. Flexible leaf-holding members 4 are secured to one cover 1, as by being riveted between anchor plates 5 to said cover. These leaf- 40 holding members extend through suitable slots or orifices of common form (not shown) in the binding edges of the leaves 6, and are slideable on the other cover 2 to adjust the covers to different thicknesses of 45 their contents. Each of these leaf-holding members is thus slidably guided at its edges in a suitable guide 7 on cover 2, and passes under an arm 8 pivoted at 9 on said cover and adapted to be swung in a direction parallel to the side or inner face of said cover and under a keeper 10 positioned at that side of said member opposite to the pivot 9. When swung into this position, the arm presses said member down against the cover 50 and clamps or holds it in the adjusted posi-

tion to which it has been drawn. When the arm is swung to its other position (shown in Fig. 2) the said member is released and may be readjusted as desired. The arm is secured against accidental disengagement from its keeper by their suitable mutually-engaging portions 11 and 12 respectively, particularly shown in Fig. 3. The arm, being preferably of spring material, is readily sprung to disengage the said 60 portions 11 and 12, and being released from the keeper, springs away from the leaf-holding member and cover 2, thus permitting the ready adjustment of said member; and owing to such spring character and to 65 the positioning of the keeper and the arm's pivot on the opposite sides of the leaf-holding member, the arm in its holding position spring-presses said member between it and said cover.

70 A stop 13 on cover 2, limits the arm in its releasing movement from swinging beyond the position of the leaf-holding member as the same is confined edgewise in the guide: thus, said member is guided and held 75 against edgewise movement by the guide 7; and by the swinging arm against such flatwise movement as would take it out of said guide.

75 Cover 2 has a roughened surface 14 immediately under the leaf-holding member, which is adapted to more securely hold, in the arm's operative or holding position, said member against sliding movement: and such roughened surface is preferably formed as 80 shown in Fig. 5, wherein the projections or teeth slope toward the binding edge of the cover and are abrupt toward its opposite edge, thus more securely holding said member against that movement which loosens or 85 slackens it.

The invention being intended to be defined solely by the claims, is not to be limited by details of construction shown or described.

100 What is claimed is:

1. In a loose-leaf binder; a pair of covers, the second of which has a guide for the edges of the leaf-holding member herein-after named; a flexible leaf-holding member 105 secured to the first cover; and an arm pivotally mounted on, and adapted to be swung in a direction parallel with the side of, the second cover, to one position in which it holds against movement said member be- 110

- tween the arm and second cover and to another position in which said member is released; the second cover having a stop adapted to limit the arm in its said releasing movement from swinging beyond the position of said member as guided in said guide.
2. In a loose-leaf binder; a pair of covers, the second of which has a keeper and also a guide for the edges of the leaf-holding member hereinafter named; a flexible leaf-holding member secured to the first cover; and an arm pivotally mounted on, and adapted to be swung in a direction parallel with the side of, the second cover, to one position in which it engages the keeper and clamps said member between the arm and second cover and to another position in which it is released from the keeper and releases said member; the second cover having a stop adapted to limit the arm in its said releasing movement from swinging beyond the position of said member as guided in said guide.
3. In a loose-leaf binder; a pair of covers, the second of which has a keeper; a flexible leaf-holding member secured to the first cover; and an arm pivotally mounted on, and adapted to be swung in a direction parallel with the side of, the second cover to one position in which it engages the keeper and clamps said member between the arm and second cover and to another position in which it is released from the keeper and releases said member; the keeper being positioned on the second cover on the opposite side of said member from the pivotal mounting of the arm; the keeper and arm having respectively mutually-engaging portions.

adapted to hold the arm against accidental disengagement from the keeper.

4. In a loose-leaf binder; a pair of covers; a flexible leaf-holding member secured to the first cover; and an arm of spring material and pivotally mounted on, and adapted to be swung in a direction parallel with the side of, the second cover, to one position in which it holds against movement said member between the arm and second cover and to another position in which said member is released; the second cover having a roughened portion under said member and adapted to secure it in the arm's holding position of said member against sliding movement.

5. In a loose-leaf binder; a pair of covers; a flexible leaf-holding member secured to the first cover; and an arm of spring material and pivotally mounted on, and adapted to be swung in a direction parallel with the side of, the second cover, to one position in which it holds against movement said member between the arm and second cover and to another position in which said member is released; the second cover having a roughened portion under said member and adapted to secure it in the arm's holding position of said member against sliding movement in that direction which slackens off said member.

In testimony whereof we have hereunto set our hands in presence of two subscribing witnesses.

WILLIAM S. PROUDFIT.
